CLAIM

The ornamental design for storage furniture, as shown and described.

DESCRIPTION

1. Storage furniture

1.1 : Isometric (top, front, left)

1.2 : Isometric (bottom, back, right)

1.3 : Front

1.4 : Back

1.5 : Left

1.6 : Top

1.7 : Bottom

The right side view is omitted because it is a mirror view of its respective left side view. The storage furniture is shown with a symbolic break in its length and width. The appearance of any portion of the storage furniture between the break lines forms no part of the claimed design. The parts shown in white color and delineated with dashed lines form not part of the claimed design.
